UNITED STATES PATENT OFFICE.

SAMUEL N. McCLEAN, OF CLEVELAND, OHIO.

TRAINING DEVICE FOR GUNS.

SPECIFICATION forming part of Letters Patent No. 772,248, dated October 11, 1904.

Application filed June 11, 1902. Renewed March 15, 1904. Serial No. 198,323. (No model.)

To all whom it may concern:

Be it known that I, SAMUEL N. McCLEAN, a citizen of the United States, residing at Cleveland, Ohio, have invented a new and useful Improvement in Training Devices for Guns, which invention is fully set forth in the following specification.

My invention relates to guns and gun-carriages, and more particularly to a device for effecting the elevating, depressing, traversing, and general training movements of the gun.

Broadly stated, the object of the invention is to provide a device whereby all the movements involved in training the gun may be effected by a single operating device, to the end that said device may impart any desired movement to the gun in sighting it within a given radius or field of action to cause it to move along any desired line or to any desired point on the target at which it may be aimed, whether said target be a fixed or a moving one.

With this object in view the invention consists in a gun and its mount which leaves the gun free to receive the usual training movements, with a pair of reciprocatory members or supports for the breech of the gun, which members or supports are so mounted as to be capable of oscillation as well as reciprocation. Preferably these two members or supports are attached to the breech of the gun or to the cradle supporting the gun, on opposite sides thereof, by means of some flexible joint, as a universal joint, and are provided with a bearing on the gun-carriage, platform, or other base, which bearing leaves the members or supports free to receive reciprocatory and oscillatory movements. In order to secure the benefits of the invention in the highest degree, this bearing for the members or supports is in the nature of a universal joint through which the member or support reciprocates.

The inventive idea involved may receive various mechanical expressions, the preferred form being one in which the gun is mounted in a cradle which is free to turn around a universal joint in order that within prescribed limits it may receive any desired movement of elevation, depression, or training. At-

tached to the opposite sides of this cradle, near the rear end thereof, are the two members or supports in the form of screws which pass through nuts which are operable to impart the reciprocatory movements to the screw, while at the same time leaving it free to oscillate.

In the drawings forming a part of this specification, Figure 1 is a broken side elevation of a field-gun and carriage having my invention applied thereto. Fig. 2 is a broken plan, and Fig. 3 is a horizontal section, of the universal joint around which the cradle moves. Figs. 4 and 5 are part-sectional part-elevational detail views showing the manner of mounting and operating the supports or members. Figs. 6 and 7 are views illustrating a modification.

Referring to the drawings, 1 is the axle of a gun-carriage, and 2 2 are twin members of a boxing on the axle, each of which members is provided with a concave face fitting the axle and a hemispherical portion 3. When said members 2 2 are assembled around the axle and retained in position by collars 4 4, they form the spherical part of a universal joint around which the gun-craddle 5 may move, the cradle having the concave member of such joint formed therein, as shown in Figs. 2 and 3, such concave member being cut away, as at 6 6, to permit the free turning movement of the cradle around the spherical parts 3 3. In assembling the parts the members 2 2 are slipped into the boxing in the cradle and pushed into position opposite each other, after which the axle is inserted and the collars 4 4 secured in place on the axle. The carriage has any suitable trail-cheeks, one of which is shown in broken elevation in Fig. 1 as a tube 7. There are two of these trail-cheeks, two supporting-screws, and operating parts therefor, and as they are similar in all respects a description for one will suffice for both. A screw 8 is jointed to an ear 9 so as to move in a transverse plane, said ear being mounted to turn and slide in a dovetailed groove 10 in the side of the cradle 5. A nut 11 in the form of a beveled gear is mounted on the screw 8 and is engaged by a second beveled gear 12, mounted on a sleeve 13 on the cheek 7 and

operated by a wheel 14, the whole being secured in position by a collar 15 around the cheek. Loosely surrounding the sleeve 13, between the wheel 14 and the gear 12, is a sleeve 16, supporting guide-brackets 17, through which the screw passes and by which it is guided. The nut 11 rests on a bearing 18, shaped to conform to the cheek 7 and moving around it, one of the guide-brackets 17 lying above the nut, so as to retain it between said bracket and the bearing 18. The screw passes through the bearing 18, and the latter moves with the screw as it oscillates. The same is true of the guide-brackets 17.

15. A modification of the device is shown in Figs. 6 and 7, in which the supporting-screws are connected to the cradle by a ball-and-socket joint 19 and are connected to the cheek of the trail by a band having flanges 20, formed, as shown in Fig. 7, to engage corresponding flanges 21 on the bracket 22. These flanges 20 and 21 are cut away to permit the parts to be turned beyond their working point and to be assembled and disassembled. The gears 25 for operating this form of the device are similar to those previously described, and the operating hand-wheel is located on the side of the trail-cheek instead of surrounding the same.

30. The operation of the device is as follows: If it is desired simply to elevate or depress the gun, the hand-wheels 14 on each cheek of the trail are operated in the same direction, thereby serving to run the screws 8 up or down, as the case may be, and for this purpose only the reciprocatory movements are necessary. If it is desired to traverse the gun-muzzle, say, to the right, this may be accomplished by running the right-hand screw up or the left-hand screw down or by simultaneously running the right-hand screw up and the left-hand one down. In short, by simultaneously operating the two hand-wheels at the same or varying rates of speed and in the same or reverse directions the muzzle of the gun may be caused to follow any desired line, and with a little practice in its manipulation it becomes possible to readily follow a moving target and keep the gun laid thereon at all times. During the up-and-down movements of the screw-supports the angle of connection between said supports constantly varies and the ear or bracket of the hinge part 9 is free to roll or slide in the flanged way 10 in the cradle.

It will be understood that while I regard the screws 8 as a desirable form of support they are illustrative only, as any other form of support with means for operating the same may be employed without departing from the spirit of my invention.

Having thus described the invention, I claim—

1. The combination of a gun, its mount, and a universal connection between them, with a

plurality of supports for the gun's breech articulated thereto on opposite sides of its central vertical longitudinal plane, and means for operating said supports, whereby all the training movements of the gun are obtained.

2. The combination of a gun, its mount, and a universal connection between them, with a plurality of oscillating reciprocatory supports for the gun's breech, and means operating said supports.

3. The combination of a gun, its mount, and a universal connection between them, with a plurality of reciprocatory supports for the gun's breech, each mounted on a universal joint, and means operating said supports.

4. The combination with a gun, its mount, and a universal connection between them, of a device operable to simultaneously elevate or depress and traverse the gun.

5. The combination with a gun, its mount, and a universal connection between them, of two oppositely-disposed independently-operable elevating devices, articulated to the gun-mount on opposite sides of its central vertical longitudinal plane.

6. The combination with a gun, its mount, and a universal connection between them, of a plurality of supports, each hinged to the gun and each mounted on a universal joint located on opposite sides of the gun's central vertical, longitudinal plane, and means operating said supports.

7. The combination of a gun, its mount, and a universal connection between them, with a plurality of screw-threaded supports secured to the gun, a nut engaging said supports, and means operating said nuts on opposite sides of the central longitudinal vertical plane of the gun.

8. The combination of a gun and its cradle mounted on a universal joint, with a pair of screw-supports jointed to the cradle, a pair of nuts on opposite sides of the central longitudinal vertical plane of the gun engaging said screws, and means operating said nuts.

9. The combination of a gun and its cradle mounted on a universal joint, with a pair of screw-supports attached to the cradle by a universal joint, nuts on said screws, bearings for said nuts restricting them from longitudinal movement, and means operating said nuts.

10. The combination of a gun, its mount and a universal connection between them, with a pair of coacting screws connecting the gun with the mount, on opposite sides of its central vertical longitudinal plane.

11. The combination of a gun, its mount and a universal connection between them, with a pair of coacting elevating and traversing screws connecting the gun to the mount, on opposite sides of its central vertical longitudinal plane.

12. The combination with a gun, of a gun-carriage and its trail, a pair of coacting screws articulated to the gun, a nut on each screw

having bearing on the respective cheeks of the trail, and means operating said nuts.

13. The combination of a gun, with a traversing device comprising a pair of coacting screws articulated to the gun, nuts on said screws, a gun-carriage having a trail, and a gear carried on each cheek of the trail engaging with said nuts respectively to operate the same.

14. The combination with a gun and its carriage and a universal connection between them, of a pair of companion coacting screws articulated thereto, a nut on each screw, a pair of gears supported on the trail of the carriage and gearing with the respective nuts, and a sleeve or bracket retaining the parts in operative relation.

15. The combination of a gun, its mount and a universal connection between them, with a pair of screw-supports articulated to the gun on opposite sides thereof, a gun-carriage

and trail, a pair of nuts on said screw-supports, one of said nuts having bearing on each cheek of the trail, gears having bearing on said trail and gearing with said nuts, and means for operating said gears.

16. The combination of a gun, a gun-carriage and trail, with a pair of screws each having a hinged and sliding connection with the gun, a nut on each screw, each nut having a bearing on one cheek of the trail, a guide for each screw supported on the respective trail-cheeks, beveled gears gearing with the respective nuts, and hand-wheels to operate said gears.

In testimony whereof I have signed this specification in the presence of two subscribing witnesses.

SAMUEL N. McCLEAN.
